UNITED STATES PATENT OFFICE.

HOWARD G. SHORTT, OF CARTHAGE, NEW YORK, ASSIGNOR OF ONE-HALF TO STEBBINS ENGINEERING AND MANUFACTURING COMPANY, OF WATERTOWN, NEW YORK, A CORPORATION OF NEW YORK.

PUMPING STEAM TRAP.

Application filed July 18, 1928. Serial No. 293,719.

This invention refers to that class of steam traps known as pumping steam traps, which have as their chief characteristic the automatic alternate filling and emptying of a receiver or tank with high temperature, condensate, boiler feed water, and the like, by the action of valve mechanism which introduces high pressure steam into a full tank to expel the contents and then vents the expelling pressure to allow the tank to refill with water.

Among the leading objects I have in view are simplicity and economy of construction, reducing the parts to as small a number as possible, and combining them in such a way that the results may be attained easily and effectively, with little wear and waste; and in fact the aim is to accomplish with a simple mechanism as much or more than has heretofore been attained with far more complicated and intricate machinery. I lay particular stress on the means whereby the lubricant is supplied to the moving parts of the valve mechanism in a novel manner so that the oil cannot enter the main receiver chamber and mingle with condensation water so as to injuriously affect the boiler or its tubes.

The invention may moreover be said to consist essentially in the construction, combination, and arrangement of parts, substantially as will be hereinafter described and claimed, including numerous details and peculiarities of the same and their obvious modifications and re-adjustments.

In the annexed drawing illustrating my invention:

Figure 1 is a front elevation of my improved pumping steam trap.

Figure 2 is a vertical section of the same on the line 2, 2, of Figure 1.

Figure 3 is a detail front view of certain features, some of which are in section, the view being taken on the line 3, 3, of Fig. 2.

Figure 4 is a vertical sectional view on the line 4, 4, of Figure 2.

Figure 5 is a detail view of the secondary rotary valve which controls the fluid pressure for operating the main water and steam vent discharge.

Similar characters of reference denote like parts throughout all the different figures of the drawing.

The trap tank or receiver A may be of any

size, shape, design, and proportions, and may be arranged with a steam condensation plant or other apparatus. The condensation water flows into the tank at some suitable point near the bottom, as for example through the opening *a*, and at the proper time when the tank is full the water is discharged through the same opening *a*. A curved pipe is often introduced into the bottom of the tank to admit and discharge the water and insure a proper water seal; I have indicated such a curved pipe in my co-pending allowed application for automatic receiver pump, filed December 17, 1927, Serial Number 240,661; and with the opening of whatever character inlet and outlet check valves are often used, but I have not illustrated these, as there are many different ways, and I do not desire to be confined to any specific kind of inlet and discharge opening and valve mechanism.

The automatic pumping of the trap tank or receiver is accomplished through the agency of high pressure steam which enters the top of tank A through an inlet port 1 after the tank A has completely filled up with water. This introduction of live steam pressure against the water when the tank is full has the function of expelling the water, and after this is done the expelling steam is vented to atmosphere or elsewhere reversely through the same port 1, so that the tank will be at liberty to refill again with water. Tank A has a removable head plate B bolted thereto by bolts *b*, and formed in front with a hollow housing or protuberance 55, into whose interior 53 the arm *c* of float C projects through opening 54 from the tank A where the float is buoyant in the liquid in the tank, rising and falling with the varying level of said liquid. The upper part of plate B has therein a steam port 1^a which joins with the port 1 in the wall of tank A to form the long port which admits to and vents steam from the tank A.

Supported in any convenient manner on the front face of head plate B, adjoining port 1^a, is a valve casing or casting 6 which is shaped and chambered and ported to provide for the reception of a main steam supply and exhaust valve, which is nearest port 1^a, and also alongside of it the secondary float-actuated control valve which supplies the steam, air, or other fluid pressure for operating the main steam valve and vent valve. The main

steam valve combines a steam supply valve 44 and a vent valve 42 in a single unit on a valve stem 43 and carrying a piston 40 united with the valve 42 below the latter, so that the piston 40, vent valve 42, stem 43 and steam valve 44, are all in one unitary solid combination which has a vertical travel in the performance of its several functions in the handling of the steam pressure which causes the trap 10 to pump.

Said casting 6 which provides these valve casings has a central chamber 49, opposite to and entered by the steam port 1^a, see Figures 2 and 4, through which chamber passes valve 15 rod 43. Below chamber 49 is a chamber 41 occupied by the piston 40 that travels up and down, and is attached to stem 43, and also at the top of chamber 41 is the vent or exhaust valve 42, operating in connection with 20 its seat 56 and controlling an opening into chamber 49 from which steam is vented into chamber 41 when valve 42 is open. Chamber 41 has a steam discharge pipe 10. Above the chamber 49 is a chamber 47 in which is the 25 steam valve 44 attached to stem 43 and operating in connection with its seat 48 to control the passage from chamber 47 into chamber 49 so as to allow steam pressure to pass from chamber 47 into chamber 49 when valve 30 44 is open. The chamber 47 has coupled thereto a steam inlet pipe 9. The lower end of casting 6 below piston 40 is closed by a screw plug 38 and below said piston is a chamber 35 39 which receives high pressure steam supplied by the secondary control valve through port 37 to lift piston 40 in the act of closing the vent valve and opening the steam inlet valve. Further, the chamber 47 is closed at the top by a cover 8 secured by bolts to the 40 top of casting 6 and having a hollow projection 45 in which is a sliding sleeve 52 secured to valve 44, and said sleeve contains a spring 46. When the pressure under piston 40 is withdrawn, the steam pressure in tank A acts 45 against the valve 42 to open the same, and is assisted by the spring 52 in so doing.

To open the aforesaid steam supply valve I employ a secondary control valve which is actuated automatically by the buoyant member 50 in the liquid in the tank A, and this actuation of the control valve introduces pressure under piston 40 to lift the same. The special construction of this control valve may vary widely. It may be a rotary valve, a slide 55 valve, or any other suitable control means.

In the example given by way of explanation, I have illustrated a rotary valve which is encased in the casting 6, the details being clearly seen in Figures 2, 3, and 5. The rotary valve lies in a horizontal position within a sleeve or bushing 13 secured within box 59 in casting 6, only a short distance from the unitary steam admission and vent member just described. Bushing 13 has a steam port 65 36 which enters the port 37 leading to cham-

ber 39 under piston 40; and bushing 13 also has an exhaust port 17 entering an exhaust port 18 in casting 6 which opens into the atmosphere or elsewhere, as shown in Figure 3.

The rotary valve member proper 14 comprises a pair of discs 26, 26, on a central body of hollow semicircular form, cut away at 11 to receive steam, said central hollow body having a port 15 leading through it and connecting at times with the bushing port 36, 75 and said valve 14 having an exhaust port 16 formed in its outer face and serving to connect the bushing port 36 with the exhaust outlet 17 when the release of fluid pressure that has opened the steam valve takes place. 80 Also the valve 14 has a round projection 57 on one end and a similar projection 58 on the other end which center the valve in its own casing or enclosure 59, which is formed on the casting 6 or otherwise applied thereto so 85 as to be substantially a part thereof.

The projection 58 has a slot 30 therein engaged by a tongue 29 on a disc 28 on the end of a shaft 27 supported horizontally in a bearing 60 that is screwed into the end of box or chamber 59, said shaft 27 being packed by a gland and packing nut 50 arranged in connection with bearing 60. The shaft 27 is a rock shaft and when rocked after it is in engagement with valve 14, the valve may be 95 shifted from one position into another. Steam is supplied to valve 14 through the high pressure steam or air pipe 12 which enters the wall of casting 6 and delivers its pressure through a port 61 that runs through 100 the wall and bushing 13 to the valve 14.

Obviously the exact shape of said hollow rotary valve 14 may vary within wide limits, provided only it has the requisite steam and exhaust ports to deliver live steam at the 105 proper time, and also to vent the used steam, in accordance with the movement of the float which transfers its action to the valve and shifts it back and forth at the right moment.

The float C has its arm c projecting through opening 54 into the far end of the enlarged boxing 55 in which it is fulcrumed on a pin 24 having a squared nut 25 cast integral thereon. The nut 25 engages the arm c so that when the arm rises or drops it will partly 115 rotate the pin 24. Pin 24 has its inner end held in a bearing in the wall of boxing 55 and its other portion carried by a bearing 62 which is screwed into the wall of boxing 55, a packing gland or nut 32 being screwed 120 upon the bearing 62 to tightly pack and hold the short shaft 24, which projects outside of boxing 55 for a short distance. Its outer end carries rigidly thereon an arm or a pair of arms 21, which are shaped as slotted links 22 to engage a pin 23 in the lower end of a connecting rod 20 which extends upward 125 vertically to a point near the rotary control valve.

The links 22 allow the float to have a cer- 130

tain amount of travel without affecting the position of rod 20. It is only when the pin 23 is in the end of link 22 that the rod is moved by the float. The upper short shaft 27 which engages the rotary valve 14 to rotate the same, has on its outer end a rigidly attached arm 31, whose outer end is pivoted by a pivot 34 in the cleft upper portion 35 of rod 20, said upper portion 35 being 10 made adjustable by the nut 33 so as to lengthen or shorten the rod 20 in order to regulate or change the throw of valve 14. By these connections therefore the buoyant member C is enabled to rotate the valve 14 and change its position in correspondence with the action of member C as it rises and falls.

Lubrication of the valves is provided through a lubricator 2 mounted on the valve 20 mechanism near the rotary valve, said lubricator being carried on an upright tube 51, whose lower end 5 screws into the top wall of the casting 6 and delivers oil into a port which feeds through a port 19 in bushing 25 13 and thus reaches the interior of the rotary valve 14. The oil flows through the various steam ports and passages along with the steam or fluid pressure and lubricates the rotary valve 14 and the piston 40. It 30 is impossible for the oil to mix with and contaminate the fluid pumped, either when it is flowing into or out of the tank, because during the tank filling period there is no pressure on the piston and what oil might 35 lie on the top of the piston is carried off through pipe 10 by the exhaust of receiver pressure, and during the discharging period the vent valve is closed so that no oil can escape into the water.

40 The operation of my improved trap will be clearly understood from the foregoing description of the parts without need of further amplification. While tank A is filling with water or condensation, or any fluid or 45 liquid, from a steam plant or whatever other source, the float C will rise with the rising of the water level, until the tank is full to the required point, and while the float is so rising, as it nears the top, the action of the lever e is drawing down the rod 20 and rotating the rotary valve 14, or moving any other valve means used in place thereof, so that the port 15 will register with the port 36, which will instantly release high pressure 50 steam or air or other high pressure fluid from pipe 12 into port 37 and permit it to act against piston 40, lifting same and closing vent valve 42 at the same instant that it opens steam valve 44, the opening of which latter causes high pressure steam from supply pipe 9 to rush through ports 1^a and 1 into receiver A and force out all the aqueous contents of said receiver through the tank discharge.

55 This of course makes the water level in

the tank to fall, and with it drops the float, until it nears the bottom of the tank or reaches the lowest normal water level, at which time, the rod 20 and rotary valve having been actuated in a direction the reverse 70 of their former movement, the valve 14 cuts off further high pressure and connects the port 36 with the discharge port 17 by causing valve discharge port 16 to cover both of said ports, so that the pressure under 75 piston 40 escapes back through these ports and out through port 18.

When the lifting pressure under the piston is removed, and the pressure in the receiver is applied to the vent valve 42 said 80 valve will open and simultaneously the steam valve 44 will shut, it being noted that the spring 46 will assist the receiver pressure in bringing this about. Hence the steam in the receiver will exhaust through pipe 10 85 during the time that the tank is again filling, after which the valves will reverse their action as before.

Many changes in the details and their operative relation may be made within the scope 90 of the claims and I reserve the right to make all such changes within the scope of the claims.

What I claim is:

1. In a pumping trap of the class described, the combination of a tank having an inlet and outlet and a steam port for carrying steam into and exhausting it from the tank, a combined vertically-movable steam inlet and vent valve device provided with a stem carrying an integral piston, a casing for said valve device having a steam chamber provided with a steam inlet and containing said steam valve, a central chamber connecting with the tank port and receiving steam at one time to deliver to the tank port and at another time allowing steam from said port to reach the exhaust, and a lower chamber having an exhaust outlet and containing the vent valve and the piston, a float-actuated control valve for supplying steam to move said piston of the combined valve device to close the vent and open the steam valve and also for exhausting said valve-operating pressure, and resilient means to assist the steam pressure in the tank to close the vent and open the steam valve after the water-expelling steam in the tank has been vented.

2. In a steam trap of the pumping class, 120 the combination with a tank having an inlet and outlet and a common steam port for delivering into and exhausting from the tank, a combined vertically-movable high pressure inlet and vent valve device provided with a piston, a casing for said valve device having a live steam chamber controlled by the steam valve, a central chamber connecting with the steam chamber and the tank steam port, and a lower chamber for venting controlled by 125 130

the vent valve and containing the piston, a control valve for the said steam and vent valve mechanism, a float in the tank, connections between the float and said control valve, and means for conveying pressure from the control valve to the said piston to lift the same and also to carry lubricant material to said piston, so that any lubricant passing the piston may be caught and discharged in the venting chamber above without entering the condensate.

3. In a pumping trap of the class described, the combination with a tank having an inlet and outlet, of a combined vertically-movable high pressure inlet and vent valve device provided with an integral piston, a casing for said valve device having a live steam chamber controlled by the steam inlet valve, a central chamber connecting with the tank, and a lower vent chamber containing the piston, said three chambers being in a vertical line, a float-controlled control valve, means for supplying fluid pressure to be delivered by said control valve to operate the combined steam and vent valve device, and exhaust means therefor, and means for supplying a lubricant to said steam line to pass with the steam and lubricate the control valve and the piston, so that any lubricant that passes the piston may have outlet with the venting steam through the vent chamber.

4. In a pumping trap of the class described, the combination with a tank having an inlet and outlet, of a high pressure steam inlet valve, a vent valve, a stem carrying both of said valves, a piston secured to said stem, a float-operated control valve which regulates the passage of high fluid pressure to actuate said piston and the valves associated with it and also regulates the exhaust of such pressure, a steam-venting chamber into which the vent valve discharges tank operating pressure, said chamber being above the piston, a lubricant container, means for carrying lubricant mixed with steam to the control valve and to the under side of the piston, so that lubricant passing the piston may be discharged with the steam and not reach the tank condensate.

5. In a pumping trap of the class described, the combination with a tank having an inlet and outlet, of a high pressure steam valve for introducing pressure into the tank when it is full of water for the purpose of expelling said water, an exhaust valve for exhausting the expelling pressure after the water has been expelled and while the tank is again filling with water, the steam valve closing when the vent valve opens, and the vent valve closing when the steam valve opens, a fluid-pressure-operated piston for jointly actuating said valves at one time, and a resilient means to supplement the internal tank pressure to operate these valves at another time, a valve for controlling the action of the piston by in-

70

roducing fluid pressure against the same, said valve having a fluid pressure inlet and a fluid pressure exhaust, a float in the tank, and means connecting the float with said control valve.

6. In a pumping trap of the class described, the combination with a tank having an inlet and outlet, of a high pressure steam valve for introducing pressure into the tank when it is full of water to expel the same, an exhaust valve for exhausting the expelling pressure after the water has been expelled, a fluid pressure operated piston for jointly actuating said valves at one time, and a resilient means to supplement the internal tank pressure to operate these valves at another time, a valve controlling the action of the piston by introducing fluid pressure against the same, said valve having a fluid pressure inlet, a lubricant inlet, and a fluid pressure exhaust, a lubricant supply feeding the lubricant inlet, in order that fluid pressure mingled with lubricant may pass to the valve mechanism without entering the tank, a float in the tank, and means connecting the float with the control valve.

7. In a pumping trap of the class described, the combination with a tank having an inlet and outlet, of a high pressure steam inlet valve, a vent valve, coupled together to work in unison, but one being open when the other is closed, a rotary control valve, a ported bushing surrounding same, a casing supporting the bushing, having a fluid pressure inlet, an exhaust, and a passage to the steam inlet and vent valves, a float in the tank, means whereby the float connects with and operates the control valve to admit fluid pressure to actuate the steam inlet and vent valves and to exhaust fluid pressure from the control valve after the tank is discharged of its aqueous contents.

8. In a pumping trap of the class described, the combination with a tank having an inlet and outlet, of a high pressure steam inlet valve, a vent valve, both on the same stem and functioning in relation to a common port to introduce high pressure steam into the tank to expel the water and then to exhaust the expelling steam after the exit of the water, a piston on the stem of the valves, a float in the tank, a rotary control valve, having a fluid pressure port and an exhaust port, a bushing surrounding it and having a fluid pressure port and an exhaust port, a casting supporting the bushing and having a fluid pressure inlet, a port leading to the piston and an exhaust port, and means connecting the float with the rotary control valve to operate the latter to supply fluid pressure to the piston to actuate the steam and vent valves.

9. In a pumping trap of the class described, the combination with a tank having an inlet and outlet, of a high pressure steam inlet valve, a vent valve, both functioning in rela-

tion to a common port to introduce steam into the tank to expel the water and then to exhaust the expelling steam after the expulsion of the water, and said valves having a common stem together with a piston on said stem, a float in the tank, a rotary control valve having a fluid pressure port and an exhaust port, a bushing surrounding it and having a fluid pressure port and an exhaust port, a casing 5 supporting the bushing and having a fluid pressure inlet, a port leading to the piston and an exhaust port, means connecting the float with the rotary control valve to operate the latter to supply fluid pressure to the piston 10 to actuate the steam and vent valves, means for supplying a lubricant to mingle with the fluid pressure in the control valve, so that the combined fluid pressure and lubricant may reach the valve mechanism and act there- 15 on without contaminating the condensate being handled.

10. In a pumping trap of the class described, the combination with a tank having an inlet and outlet, of a steam inlet valve and a 25 steam vent valve for the tank, both functioning in relation to a common port entering the tank, a piston connected with said valves for moving them, a secondary fluid pressure rotary control valve supplying fluid pressure 30 to actuate said piston, said valve consisting of a hollow cylinder having parallel discs and a cutaway portion and also having a fluid pressure port and an exhaust port, a bushing enclosing the valve and having a fluid pressure 35 and an exhaust port, a valve casing carrying the bushing and having a fluid pressure inlet, a fluid pressure outlet to the piston, a fluid pressure exhaust and an oil inlet, a float in the tank which rises and falls with the water 40 level, and having an arm, a pin in the tank wall on which the arm is fulcrumed, levers on said arms and on the rotary valve, a part of same having slotted links to permit the float arm to have a certain range of movement

without disturbing the rotary valve, and an 45 adjustable link connection between rotary valve arm and the arms on the fulcrum pin, all arranged so that the float may control the flow and exhaust of the fluid pressure that 50 operates the piston, and resilient means operating to move the steam and vent valves in a direction opposite to that in which they are moved by the piston.

11. In a pumping trap of the class described, the combination of a tank having an 55 inlet and outlet, and a steam port, or ported head plate whose port connects with the tank port, a combined steam inlet and vent valve having a common stem and a piston on said 60 stem, a valve casing for said combined valve having a steam inlet chamber and seat therein for steam valve, a middle combined steam inlet and vent chamber opening into the aforesaid port, and a vent chamber containing 65 piston and vent valve and seat for the latter, said steam chamber and said vent chamber communicating with the middle chamber as the valves open and close, and a secondary rotary control valve having a fluid pressure port and an exhaust port, a bushing 70 containing said rotary valve and having a fluid pressure port and an exhaust port, a valve casing for said rotary valve having a fluid pressure inlet, an oil inlet, an exhaust outlet and a fluid pressure port leading to the 75 piston chamber, a float in the tank, an arm thereon, a fulcrum hung in the head plate for said arm, and leverage means connecting said arm with the rotary valve and adapted to rotate the same during the movements of the 80 float on the water level so as to control the passage and exhaust of the operating fluid pressure for the combined steam inlet and vent valve mechanism.

In testimony whereof I hereunto affix my 85 signature.

HOWARD G. SHORTT.
